UNITED STATES PATENT OFFICE

167,940

CHAIR

James M. Hofgesang, San Francisco, Calif.

Application June 30, 1952, Serial No. 20,417

Term of patent 14 years

(Cl. D15—8)

To all whom it may concern:

Be it known that I, James M. Hofgesang, a citizen of the United States of America, residing in the city and county of San Francisco and State of California, have invented a new, original, and ornamental Design for a Chair, of which the following is a specification, reference being had to the accompanying drawing, forming a part thereof.

The figure is a perspective view of a chair, showing my new design.

I claim:

The ornamental design for a chair, as shown.

JAMES M. HOFGESANG.
